FRED O. NELSON AND CLIFFORD A. FOGL, OF PITTSBURGH, PENNSYLVANIA

PRICE CARD DISPLAY HOLDER

Application filed May 31, 1930. Serial No. 458,746.

Our invention relates to a holder for price cards, and while primarily intended for displaying price cards, it will be obvious that the device may be employed for any other display purposes wherein it is found to be applicable.

Important objects of the invention are to provide a display holder, of the character described, which carries and houses a plurality of price cards capable of being interchangeably positioned therein for selectively displaying any numeral or a multiplicity of the combination of numerals, which is adaptable for displaying information on both the front and rear sides thereof, which may be readily attached in the displaying position, and which embodies novel means for facilitating the insertion of the price cards therein and the removal of the latter therefrom.

Further objects of the invention are to provide a device, of the class stated, which is simple in its construction and arrangement, durable and efficient in its use, compact, attractive in appearance, conveniently operable and comparatively inexpensive to manufacture and maintain.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawings wherein like numerals of reference designate corresponding parts throughout the several views:—

Figure 1 is a front view of a price card display holder constructed in accordance with the invention.

Figure 2 is an end view thereof.

Figure 3 is a transverse sectional view on line 3—3, Figure 1.

Figure 4 is a rear view of our improved price card display holder.

Figure 5 is a plan view of the blank prior to the formation of the device therefrom.

Figures 6, 7 and 8 are, respectively, front,

edge, and rear views of one of the price display cards.

Referring in detail to the drawings 1 denotes the casing of our improved holder, which casing is preferably constructed from 55 an integral piece of sheet metal, or any other suitable sheet material.

The casing 1 is rectangularly oblong in contour and comparatively thin. The casing 1 comprises a front wall 2 and a rear 60 wall 3, which are disposed parallel to and spaced from each other, to provide a chamber 4 therebetween. The chamber 4 is provided with an open top 5, a closed bottom 6 and closed ends 7.

The casing 1 is formed by bending the blank 1', from which it is formed, along the dash lines 6', thereby providing the bottom 6. The ends of the casing 1 are closed by bending the end margins 7 of the rear 65 wall 3 forwardly along the dash lines 8, and then bending the end margins 9, of the front wall 2 rearwardly along the dash lines 10 to overlap the rear wall end margins 7. The front and rear walls 2 and 3, are secured together adjacent to their upper ends by a pair of ears 11, which are carried by the front wall 2 and bent along the dash lines 12 to overlap the rear wall 3, as clearly 70 shown in Figure 4.

An attaching plate 13 is formed integral with the top of the rear wall 3, and is rearwardly offset, as at 14, to dispose the rear surface thereof on the vertical plane of the rear surface of the ears 11, so that the attaching plate 13 will seat flatly against the supporting member from which it may be suspended.

The attaching plate 13 is provided with a centrally disposed slot 15 for the passage 80 of a supporting pin or the like, when suspending the holder from the latter. The device may also be suspended by a prong 16, which is stamped and extends rearwardly from the rear wall 3, centrally of and 85 adjacent to the top of the latter.

The chamber 4 is divided, centrally of its length, by a vertically disposed partition 17, which is stamped from the rear wall 3 and extends forwardly into a verti- 100

cally disposed pocket 18 formed in the front wall 2 of the casing 1.

Two packets of display cards 19 are carried in the chamber 4, and are disposed in the latter on respective sides of the partition 17. The latter maintains the packs of display cards 19 separate and distinct from each other.

Each pack comprises five display cards 19, and a different numeral 20 is displayed on each side of each display card of each pack, as shown in Figures 6 and 8. As there are but ten different numerals, all of the latter are contained in each pack, 15 there being five display cards in each pack, and each of the cards displaying a numeral, on each side thereof. The display cards 19, while preferably constructed from opaque celluloid, parylin or analogous material, may also be made from paper or 20 any other suitable material meeting requirements.

The front and rear walls 2 and 3, of the casing 1, are each provided with a pair of 25 rectangularly shaped openings respectively indicated at 21 and 22. The pair of openings 21 in the front wall 2, are disposed parallel to and register with the pair of openings 22 in the rear wall 3. The obvious 30 purpose of the openings 21 and 22 is to display the numerals 20 on the card 19, which is positioned directly in the rear thereof, or foremost in its pack.

Our improved price card holder is primarily intended for displaying the prices 35 of commodities in grocery stores. The prices of such commodities are usually indicated at so much per pound, per dozen, or per unit, and seldom exceed one dollar. 40 With the embodiment of two packs of display cards 19, as herein set forth, any price from one cent to ninety-nine cents may be selectively displayed at one side of the device.

45 The price card holder is primarily intended for displaying the cards at the front thereof only when provided with card packs bearing the numerical designations as hereinbefore stated. However, by employing 50 cards of required numerical designations, the rear side of the holder 1 may also be utilized for price display purposes.

The top of the front wall 2 is provided with a forwardly projecting flange 23 to 55 facilitate the manipulation of the holder when attaching, removing or replacing the latter. The flange 23 further facilitates the insertion of the display cards 19 into the chamber 4. The removal of the display 60 cards 19 from the chamber 4 is readily accomplished by grasping either pack with the thumb and finger through registering openings 21 and 22 and pushing the card pack upwardly through the open top 5, of the chamber 4.

It will be apparent, that while the chamber 4 is divided to receive but two packs of display cards, the holder, may be constructed to carry any desired number of such packs, and to display any number of cards by providing a corresponding number of openings in the walls of the casing.

The present invention provides a most efficient device of its kind, which is adapted for compactly housing and changing the necessary display elements required for its use. It will be evident, that the principle of the invention may readily be involved in devices employed for displaying any desired information other than price cards, as set forth in the embodiment of the invention herein disclosed.

What we claim is:—

1. A card display holder, of the character described, comprising in combination, a casing constructed from an integral sheet of material bent upon itself to provide spaced and parallel disposed front and rear walls having a closed bottom, the end edge margins of said rear wall being bent forwardly, the end edge margins of said front wall being bent rearwardly and overlapping the respective forwardly extending edge margins of said rear wall, ears carried by the end edge margins of said front wall and engaging said rear wall for securing said front and rear walls in their relative positions, said front wall being provided with a plurality of openings.

2. A card display holder, of the character described, comprising in combination, a casing constructed from an integral sheet of material bent upon itself to provide spaced and parallel disposed front and rear walls having a closed bottom, the end edge margins of said rear wall being bent forwardly, the end edge margins of said front wall being bent rearwardly and overlapping the respective forwardly extending edge margins of said rear wall, ears carried by the end edge margins of said front wall and engaging said rear wall for securing said front and rear walls in their relative positions, said front and rear walls being formed with a plurality of similarly disposed openings.

3. A card display holder, of the character described, comprising in combination, a casing constructed from an integral sheet of material bent upon itself to provide spaced and parallel disposed front and rear walls having a closed bottom, the end edge margins of said rear wall being bent forwardly, the end edge margins of said front wall being bent rearwardly and overlapping the respective forwardly extending edge margins of said rear wall, ears carried by the end edge margins of said front wall and engaging said rear wall for securing said front and rear walls in their relative posi-

tions, and a vertically disposed partition being carried by one of said walls and extending into the casing against the other of said walls.

5 4. A card display holder, of the character described, comprising in combination, a casing constructed from an integral sheet of material bent upon itself to provide spaced and parallel disposed front and rear walls 10 having a closed bottom, the end edge margins of said rear wall being bent forwardly, the end edge margins of said front wall being bent rearwardly and overlapping the respective forwardly extending edge margins 15 of said rear wall, ears carried by the end edge margins of said front wall and engaging said rear wall for securing said front and rear walls in their relative positions, said front and rear walls being formed 20 with a plurality of similarly disposed openings, and a vertically disposed partition being carried by said rear wall and extending into a pocket formed in said front wall.

5 5. A card display holder, of the character 25 described, comprising in combination, a casing constructed from an integral sheet of material bent upon itself to provide spaced and parallel disposed front and rear walls having a closed bottom, the end edge margins 30 of said rear wall being bent forwardly, the end edge margins of said front wall being bent rearwardly and overlapping the respective forwardly extending edge margins 35 of said rear wall, ears carried by the end edge margins of said front wall and engaging said rear wall for securing said front and rear walls in their relative positions, said front and rear walls being formed 40 with a plurality of similarly disposed openings, a vertically disposed partition being carried by said rear wall and extending into a pocket formed in said front wall, and an attaching plate being formed with the top of said rear wall.

45 6. A card display holder, of the character described, comprising in combination, a casing constructed from an integral sheet of material bent upon itself to provide spaced and parallel disposed front and rear walls 50 having a closed bottom, the end edge margins of said rear wall being bent forwardly, the end edge margins of said front wall being bent rearwardly and overlapping the respective forwardly extending edge margins 55 of said rear wall, ears carried by the end edge margins of said front wall and engaging said rear wall for securing said front and rear walls in their relative positions, said front and rear walls being formed 60 with a plurality of similarly disposed openings, a vertically disposed partition being carried by said rear wall and extending into a pocket formed in said front wall, an attaching plate being formed with the top of 65 said rear wall, and an attaching plate being

formed with the top of said rear wall and being rearwardly offset relatively to the latter.

In testimony whereof we affix our signatures.

FRED O. NELSON.
